ANTI-PICK LOCK

Louis Gutman, Fitchburg, Mass., assignor to Independent Lock Company, Fitchburg, Mass., a corporation of Massachusetts

Filed June 24, 1959, Ser. No. 822,513
5 Claims. (Cl. 70—38)

This invention relates to a pickproof lock, and more particularly to a pickproof pin tumbler lock.

Known to me is the provision in a lock assembly of a pin tumbler having means which endeavor to minimize use with an unwarranted key by the employment of an auxiliary pin or pins which come into play when an improper key is used, or which is subject to plug rotation by picking tools which progressively position the parting lines of the driver and follower pins along the plug bearing because of the tolerance clearance of the plug within the plug casing. Such picking means rely, in a measure, upon the bolt resistance or positive pressure engagement between the cylinder plug or cam thereof with the bolt actuating mechanism. The provision in such assembly of pickproof means in the nature of auxiliary tumbler pins is not effective with a species of picking technique which combines the picking operation with tapping to recoil the pins of the locking or jamming assembly.

In accordance with my invention, it is an object thereof to provide a pin tumbler cylinder lock installation which effectively overcomes a species of lock picking technique to jam the cylinder and indicate tampering. By my invention I combine with the known pin tumbler assembly, an auxiliary pin tumbler plug jamming component and locking means therefor which have a spring biased auxiliary driving pin. I further augment the elements of security by combining therewith in the plug and bolt operating means, a lost motion coupling, wherein the auxiliary pin effectively blocks said plug movement before effective engagement between said bolt operated means and plug, to drive an auxiliary driving pin into engagement with an unsupported follower pin before effective engagement between said bolt operating means and the jamming means actuated by said plug.

Still more specifically, it is an object of my invention to overcome a species of lock picking technique by the combination with a pin tumbler assembly of an auxiliary pin tumbler plug jamming assembly which becomes effective to be driven into engagement with an unsupported follower pin, characterized by a locking driver pin which is spring biased on both its leading and trailing ends to spring bias the locking pin in opposite directions of movement.

Still further, my invention has for its object to provide in a pin tumbler lock, a security feature having an auxiliary driver pin to jam the cylinder plug upon unauthorized endeavors to manipulate the plug by a picking technique, characterized by the incorporation therein of an auxiliary pin tumbler driver and blocking pins to assure entry of such jamming expedient upon unauthorized movement of the key plug.

To attain these objects and such further objects as may appear herein or be hereinafter pointed out, I make reference to the accompanying drawing, forming a part hereof, in which—

FIGURE 1 is a longitudinal fragmentary section of a padlock illustrating my invention;

FIGURE 2 is a magnified section taken on the line 2—2 of FIGURE 1 in the locked position of the padlock;

FIGURE 3 is a view similar to FIGURE 2, with the padlock bolt turned to the shackle releasing position;

FIGURE 4 is an exploded perspective view of the plug and cam assembly;

2

FIGURE 5 is a fragmentary section taken on the line 5—5 of FIGURE 3;

FIGURE 6 is a section taken on the line 6—6 of FIGURE 5 with the key removed;

5 FIGURE 7 is a view similar to FIGURE 6 with the key plug in a partially angular position;

FIGURE 8 is a view similar to FIGURE 7 with the auxiliary pin in the follower pin driving position;

FIGURE 9 is a section taken on the line 9—9 of FIGURE 8;

FIGURE 10 is a section on the line 10—10 of FIGURE 6;

FIGURE 11 is a fragmentary plan view illustrating my invention as applied to a lock cylinder;

15 FIGURE 12 is a fragmentary section taken on the line 12—12 of FIGURE 11;

FIGURE 13 is a longitudinal fragmentary sectional view illustrating another embodiment of my invention;

FIGURE 14 is a section taken on the line 14—14 of FIGURE 13;

FIGURE 15 is a longitudinal sectional view to illustrate a still further embodiment of my invention;

FIGURE 16 is a fragmentary sectional view taken on the line 16—16 of FIGURE 15;

25 FIGURE 17 is a fragmentary sectional view of a still further embodiment of my invention;

FIGURE 18 is a section on the line 18—18 of FIGURE 17.

Making reference to the drawing, I illustrate my invention, in one embodiment thereof, in connection with a padlock 10 having an armored shell 11 closed by a cap 12. The shell and cap are held together by draw pins 13, suitably staked at opposite ends after enclosing a pin tumbler assembly casing 14, and a spring 35 projected shackle 15, the branches 16 and 17 whereof are arranged to be locked by the swinging bolt 18, pivoted on the pin 19 to extend the opposite ends 20 and 21 into corresponding locking slots of the shackle, in a well known manner.

40 The bolt end 21 may be provided with extensions 22 serving as a limiting stop in one direction, and a secondary limiting stop 23 in the opposite direction, whereby in all positions of the shackle, the shackle is held against displacement by the usual shackle spring 24.

45 The bolt 18 is spring biased into locking position as shown in FIGURE 2 by the spring 25. The bolt includes a pin 26 which extends adjacent the terminus of the pin tumbler casing and upon movement from the position shown in FIGURE 2 to the position shown in FIGURE 3, is calculated to release the shackle under the biasing influence of the shackle spring 24.

50 The pin tumbler assembly casing 14 has a plug assembly 28 extended into its plug bearing 27, which plug assembly is held against displacement by the cam plate 29 connected by the usual locking screws for keying engagement with the plug. The cam plate includes a stop lug 30, radially extending therefrom, and a cam 31 axially extending therefrom, having a cam face 32 arranged to move in the path of movement of the bolt pin 26 and abut the same.

55 In the construction as shown, a lost motion coupling exists between the cam face 32 and the bolt pin 26 so that a movement of a relatively large angle is required before the cam face 32 engages the bolt pin 26, the purpose of which will appear more clearly as this description proceeds.

60 The pin tumbler lock casing previously described has a plurality of pin tumbler bores 33, within which spring biased driver pins 34 are located, six in number being shown, and which cooperate in the usual way with follower pins 35. Corresponding lengths of the driver pins and follower pins are illustrated in FIGURE 1 to show

the position of the driver and follower pins aligned at the parting line of the plug bearing 27, when so positioned by a proper key K, which has been cut to bring the various segments into alignment, as will be understood, thereby supporting the parting line of the pins for rotation.

It will be understood that when the bores 33 of the pin tumbler casing and the bores 36 of the plug are radially aligned and unsupported by the key, the driver pin will project into one bore 36 to block rotation of the cylinder plug.

In accordance with my invention, I provide the cylinder casing 14 with one or more auxiliary bores 37, radially directed with regard to the plug axis and axially aligned with one or more of the plug bores 36. One bore 37 is illustrated and is in the sixth position with respect to the plane common to the sixth pin tumbler 34.

Angularly, the bore 37 is displaced for a distance less than the angle for bringing the camming face 32 into contact with the bolt pin 26, previously described. The auxiliary bore 37 is fitted with an auxiliary pin 38, having a rounded or cammed leading edge 39 and having its trailing edge 40 substantially flat and under biasing influence by the biasing spring 41, of materially reduced diameter with respect to the diameter of the bore 37, thereby exposing a substantial portion of the flat area 40 to either side of the biasing spring 41.

Transversely directed and intersecting the boring 37 and, in the illustration, in parallelism with the axial line of the plug, there is provided a boring 42 into which is positioned a locking pin 43 under the biasing influence of the biasing spring 44, thereby positioning the lock pin 43, in one position, to have its leading edge 45 in contact with the side of the auxiliary pin 38 (see FIGURE 10).

It will be observed that in another position (see FIGURE 9), the locking pin 43 may extend to have its leading edge 45 in engagement with the trailing edge 40 of the auxiliary pin 38 when the auxiliary pin 38 is projected across the parting line of the plug and into a bore 36 of the plug in an unsupported position of a follower pin 35.

The biasing spring 44 for the locking pin 43 is preferably of greater expansive force than the auxiliary driving pin spring 41, so that when a position as shown in FIGURE 1 is achieved, the locking pin 43 is capable of being biased in opposite directions of movement, in one direction by the spring 41 and in another direction by the spring 44.

The sharp, abrupt or flat trailing edge 40 of the auxiliary pin 38 prevents reverse driving movement of the locking pin 43 when the plug is in the position shown in FIGURE 9.

The camming face 39 on the leading edge of the auxiliary pin 38 assures and accelerates entry of the auxiliary pin 38 across the parting line and into the correspondingly located bore of the plug in an unsupported condition of a follower pin there located.

In use, the construction resists picking by a picking technique which leaves one or more of the follower pins adjacent the parting line in an unsupported condition under plug turning pressure. The lost motion gap prevents control of rotary movement and thereby, as the turning movement of the plug approaches alignment of a plug bore with the auxiliary pin bore, there is an uncontrolled movement or release by the plug and an accelerated entry engagement is effected by the auxiliary pin 38 into the unsupported bore of a follower pin 35 across the parting line of the plug, with a blocking movement of the locking pin 43 against the trailing edge 40 of the auxiliary pin 38. The flat, inter-engaged faces 40 and 45 make the movement of the auxiliary pin irreversible, especially under the biasing influence in opposite directions of movement of the springs 41 and 44.

It will be observed that while I have shown the auxiliary pin in the plane corresponding to the sixth pin tumbler position as the preferred form of my invention in that this is the least accessible for picking, I may alter

the position along any of the pin tumblers or I may include a plurality of such auxiliary pin assemblies so that if one fails to be moved into blocking position, another would become effective.

5 While I have described and illustrated my invention in connection with a padlock, it will be understood that the principle thereof may be appreciable to a variety of installations in which pin tumblers are employed.

In FIGURES 11 and 12 I show a pin tumbler casing 10 46 which may be used with a mortice lock. In this construction the plug assembly 28a as above described is fitted within the casing. Affixed to the plug is a cam driver 47 coupled to the cam 48 for lost motion driving by the finger 49 extending into the arcuate slots 50, the 15 assembly being held on the key of the plug by a known spring retaining ring 51. The slots 50 have shoulders 52 limiting the angular extension so that driving connection between the plug 28a and the cam driver 47 does not occur for a partial rotation. This is calculated to be of the magnitude to bring the plug bores into alignment with the auxiliary driving pin bore 37a before contact of the cam 47 is made with the bolt operating mechanism, to effect the same relationship of lost motion as described in connection with the prior embodiment.

20 In the embodiment of FIGURES 13 and 14, fragments are shown of a cylindrical door knob adapted to be interfitted in a door knob having key control of a cylinder in accordance with the United States patent to Gilbert No. 2,803,958. Here a plug 28b is fitted into the door knob, with the anti-picking assembly as previously described. The terminal of the plug 28b is formed with spaced lugs 31b which are quadrants defining small cam surfaces 32b, between which the cam driver bar 26b is located and extends fixedly from the dog driving cam 18b 35 which, for all practical and functional purposes, is equivalent to the bolt operating means 18 and 26 described in connection with the padlock and, therefore, the lost motion effect between the plug 28b and the bar 26b is intended to come within the terms of the claims calling 40 for "bolt operating means."

In FIGURES 15 and 16, there is illustrated another embodiment of my invention in which the plug 28c is adapted to be fitted within a cylindrical knob lock assembly for key operation through the knob, having the features of anti-picking previously described and in which 45 the plug has extended therefrom a tailpiece 26c coupled to the key cam 18c by a lost motion coupling effected by the spaced lugs 31c, 31c, corresponding in function to the bolt operating means previously described. Lost motion coupling is effected by the limited angular displacement of the lugs 31c, 31c in relation to the tailpiece 26c.

50 In FIGURES 17 and 18 there is exemplified still a further form of key operated assembly suitable for installation in cylindrical door knob constructions known to those skilled in the art wherein a plug 28d and its corresponding casing is fitted with a door knob for key control of the latch mechanism.

In this embodiment, the plug 28d is fitted with the pickproof construction previously described. The key cam 18d has fitted in the base thereof a keying disk 18e 60 through which extends the driver bar 26d, to engage the lugs 31d which are spaced apart to provide the lost motion coupling between the plug 28d and the bolt operating mechanism under the influence of the key cam 18d, as will be readily understood from the description given 65 in connection with the prior embodiments.

70 By the invention described, a pin tumbler cylinder having pickproof features and capable of indicating tampering may be embodied wherever pin tumbler installations are employed and it is desired to have a clear knowledge of such attempted unwarranted entry.

Having thus described my invention and illustrated its use, what is claimed as new and is desired to be secured by Letters Patent is:

75 1. A pin tumbler cylinder lock comprising a casing hav-

ing a row of primary pin tumbler bores within which are guided spring biased driver pins, a plug bearing in said casing, a key plug mounted for rotation in said plug bearing having complementary bores and having follower pins cooperative with said driver pins for locking said key plug except by predetermined key operation which aligns said driver pins and follower pins along the parting line between said key plug and said casing, bolt operating means carried by said lock, a lost motion coupling between said key plug and said bolt operating means effective to engage and actuate said last named means upon rotary movement of said key plug, an auxiliary pin tumbler plug jamming assembly having a spring biased auxiliary driver pin on said casing terminating in said plug bearing, said auxiliary driver pin being coaxially aligned with one of said follower pins when said key plug is displaced a predetermined rotary distance from the locked position thereof, said rotary distance being less than the rotary movement necessary to engage said coupling with said bolt actuator means whereby said auxiliary driver pin effectively blocks said key plug movement before effective engagement between said bolt operating means and said lost motion coupling when said follower pin is aligned with said auxiliary driver pin and said follower pin is unsupported by a key.

2. A pin tumbler cylinder lock in accordance with claim 1 wherein said casing has a spring biased auxiliary driver locking pin transversely guided across the path of said auxiliary driver pin for engaging the trailing end of said auxiliary driver pin to block the same in jamming position when said auxiliary driver pin engages an unsupported follower pin.

3. A pin tumbler cylinder lock in accordance with claim 1 wherein the leading edge of said auxiliary driver pin has a cammed face to accelerate entry engagement with said key plug.

4. A pin tumbler cylinder lock in accordance with claim 1 wherein said casing has a spring biased locking driver pin transversely guided across the path of said auxiliary driver pin for engaging the trailing end of said auxiliary driver pin to block the same in jamming posi-

tion when said auxiliary driver pin engages an unsupported follower pin, and said auxiliary driver pin is biased at its trailing end by a coil spring, said coil spring in said jamming position of said auxiliary driver pin being projected across the path of said locking driver pin to form a blocking retainer against which said locking driver pin is biased.

5. A padlock including a spring biased bolt to release the shackle thereof, a key operated pin tumbler cylinder for actuating said bolt, said cylinder comprising a casing having a row of primary pin tumbler bores within which are guided spring biased driver pins, a plug bearing in said casing, a key plug mounted for rotation in said plug bearing having complementary bores and having follower pins cooperating with said driver pins for locking said key plug except by predetermined key operation which aligns said driver pins and follower pins along the parting line between said plug and casing, a cam extending from said key plug having bolt operating means effective upon rotary movement of said key plug of a predetermined magnitude to engage said bolt, an auxiliary pin tumbler plug jamming assembly having a spring biased auxiliary driver pin on said casing, terminating in said plug bearing, said auxiliary pin being coaxially aligned with one of said follower pins when said plug is displaced a predetermined rotary distance from the locked position thereof, said rotary distance being less than the rotary movement necessary to engage said bolt operating means with said bolt whereby said auxiliary driver pin effectively blocks said key plug movement before effective engagement between said bolt operating means and said bolt when said follower pin is aligned with said auxiliary driver pin and said follower pin is unsupported by a key.
